BURT F. UPHAM, OF CHICAGO, ILLINOIS, ASSIGNOR TO SOUTHGATE MACHINERY COMPANY, OF BOSTON, MASSACHUSETTS, A CORPORATION OF MASSACHUSETTS.

SHEET-DELIVERY MECHANISM.

1,125,218.

Specification of Letters Patent. Patented Jan. 19, 1915.

Application filed November 14, 1911. Serial No. 660,224.

To all whom it may concern:

Be it known that I, BURT F. UPHAM, of Edgewater, Chicago, in the county of Cook and State of Illinois, have invented certain new and useful Improvements in Sheet-Delivery Mechanisms; and I hereby declare that the following is a full, clear, and exact description thereof, reference being had to the accompanying drawings, which form part of this specification.

This invention is a novel improvement in sheet delivery apparatus, and is especially designed and adapted for use with rotary sheet printing presses, but may be used in connection with other machines operating upon sheets of paper or the like.

One of the principal objects of the invention is to enable alternate sheets coming from the press to be deposited upon different receiving tables, or sheet piling trucks; in other words one sheet to be dropped upon one receiving table or truck, and the next upon the other table or truck. In this way the sheets can be delivered very rapidly yet each sheet will have the time ordinarily required for delivering two sheets to settle upon its receiving table, and therefore the ink on each sheet will have that much more time to set before another sheet is deposited upon the pile.

The invention in brief comprises means for receiving sheets from a printing press, or other machine, and successively transferring them onto some one of an endless series of carriers; each carrier preferably consists of a set of parallel tapes connected to adjacent endless chains, which run in parallel planes and are preferably traveled at a surface speed equal to that of the press cylinders. The sheet carriers are attached to these chains at suitable distances apart, and the chains are so arranged and timed that each carrier will receive a sheet at one point, and carry such sheet forward to and over the receiving table or point of deposit; and when the sheet arrives at such point it is arrested by devices or grippers which engage the tail end of the sheet. These tail grippers are preferably arranged to move on an arc of a circle and to engage the sheet when at the highest point of the arc, and then rock forward in the direction of travel of the carrier a short distance sufficient to cause the tail end of the sheet held by such grippers to be slightly low,

ered, so that the next following sheet carrier may pass above and over the sheet being held by such grippers. When the carrier supporting the sheet engaged by the grippers has moved on from beneath such sheet the grippers release the sheet, which then drops onto the receiving table; and the grippers return to position to engage another sheet brought forward by a carrier.

In the preferred form of the invention two delivery tables are provided arranged end to end, and the endless tapes are arranged to move the sheet carriers successively over both tables; and two sets of grippers are provided respectively adapted to engage the tail ends of the sheets, as they are brought forward to and over the respective tables, and to hold such sheets until the sheet carriers have passed from beneath same, and then release the sheets, in the manner described. In this way every alternate sheet will be delivered onto one table, and every other sheet onto the other table.

I will now explain the invention in detail with reference to the accompanying drawings, which will enable any one skilled in the art to properly adapt the invention to printing presses, and other machines.

In the drawings—Figure 1 is a side elevation of the complete delivery mechanism with some parts broken away. Fig. 2 is a top plan view of Fig. 1. Fig. 3 is an enlarged detail view of one of the sheet gripping devices showing it in sheet holding position in full lines, and in sheet taking position in dotted lines. Fig. 4 is a similar view showing one set of sheet holding grippers in retracted position in full lines, and in sheet taking position in dotted lines. Figs. 5 and 6 are enlarged detail views of the sheet carrier.

In said drawings 1 designates a transfer reel which is adapted to receive sheets indicated at S coming from a press or other suitable machine, not shown. This transfer reel 1 is provided with grippers 1^a which are suitably operated so as to release the sheet at the proper point of revolution of the reel and allow the sheet to pass over suitably arranged bridge or guide fingers 2 onto the sheet carrier.

Each sheet carrier preferably comprises a number of tapes 3^a attached to metal loops 3^b attached to the links of opposite

endless chains 3^c, see Figs. 5 and 6, which chains may be of any suitable construction. Such a set of tapes constitutes a very light pliable carrier, which can easily traverse 5 or follow the path of the chain 3^c. The opposite chains 3^c are arranged in parallel vertical planes and have an upper horizontal run extending from sprocket gears 3^d on stub shafts 3^e adjacent the reel 1 to and 10 over sprocket gears 3^f on studs 3^h at the rear end of the machine; then down over gears 3ⁱ on studs 3^j; then forward to and under gears 3^k on studs 3^m, and then up to sprocket gear 3ⁿ. These endless chains may be driven 15 by means of pinion 3^o on stud shafts 3^e meshing with pinions 4^a on a shaft 4. One of the pinions 4^a is shown as of double width and meshes with a gear 1^b on the shaft of reel 1. As shown there are six 20 such sheet carriers in the series, but more or less may be used according to the length of the chain and the number of receiving tables upon which it is desired to deposit sheets.

25 The carriers are traveled, preferably at the speed at which the sheets S are fed forward over the reel 1, and are so timed that as each sheet passes from the reel 1 over the fingers 2 it passes onto one of the carriers 3. The successive sheets coming from the reel 1 are delivered onto successive carriers 3 as they pass onto the upper run of the chains 3^c; and the sheets are carried bodily by the carriers to and over the receiving tables T, T', two of which are shown arranged side by side. Such tables may be of any ordinary or preferred construction, and may be mounted on trucks such as are customarily used in printing 30 offices.

When the sheets have been brought over the tables T, T' by the chains each sheet is seized by its tail end by suitable means, sets of grippers 5, 5^a being shown in the drawings, and as these are constructed alike the description and operation of one will explain the other; and they are illustrated in detail in Figs. 3 and 4. The said grippers are adapted to seize the tail ends of the 45 sheet and arrest the movement of the sheets while the carriers continue to move on from beneath the sheets. The grippers are also adapted when they seize a sheet to drop slightly below the path of travel of the carriers on the upper run of the chain, so that while the grippers hold a sheet (and the carrier which supports such sheet slips from under it) a following carrier may pass on over the arrested sheet without rubbing or 50 smearing the latter. When the carrier which supports the sheet has moved entirely from beneath it the grippers release the sheet and the latter drops upon the receiving table T or T'.

60 When the alternate sheets are deposited

upon tables T, T' they may be simultaneously dropped thereon; and when the machine is operating in this manner it will be seen that each sheet has the time required for printing of two sheets for its delivery 70 onto the table, and the ink is given that much longer time to set before another sheet is deposited thereon.

Referring to Figs. 3 and 4; each set of tail grippers (5, 5^a) comprises a set of underlying gripping fingers 5^b which are attached to a rock shaft 5^e journaled in the side frames of the machine; and co-acting with each finger 5^b is a corresponding movable finger 5^c, which is mounted upon a rock 75 shaft 5^d journaled in arms 5^f attached to the shaft 5^e. On the shaft 5^d is mounted a double armed lever, one arm 5^g of which is adapted to engage a cam-plate 5^h attached to the side of the frame; and the other arm 5ⁱ of said lever is adapted to engage a cam-plate 5^j also attached to the side of the frame. The parts are so proportioned and arranged that when shaft 5^e is rocked to the right, arm 5ⁱ will engage cam 5^j and be 80 depressed, and cause shaft 5^d to rock and open the grippers as indicated in Fig. 3. And if shaft 5^e is rocked to the left the grippers 5^c will be closed against grippers 5^b and cause the engagement of arm 5^g and 85 cam 5^h.

Each shaft 5^e is provided with a toothed segment 5^m which meshes with a toothed segment 6^m on a stub-shaft 6 journaled in the side of the frame; and the stub-shafts 100 6 are provided on their outer ends with crank arms 6^a which are pivotally connected to a link 6^b, so that both sets of grippers may be actuated simultaneously. The stub-shaft 6 nearest the reel is provided with an arm 6^c which engages a cam 7, so shaped as to actuate shafts 6 and cause them through their connections to operate the sets of tail grippers at the proper time and cause them to seize, hold and release the 105 sheets in the manner described. As shown, arm 6^c carries a stud or roller engaging a cam race in the cam 7. Said cam 7 may be journaled upon a stud 7^a attached to the side of the machine, and may be driven by 110 means of a pinion 7^b, attached to the cam, meshing with a pinion 7^c on a stub-shaft 7^d, pinion 7^c being fast to a larger pinion 7^e which meshes with an intermediate gear 7^f mounted on a stud 7^g, and in turn meshing 115 with a pinion 1^g on the shaft of the reel 1.

The parts are so timed that each sheet will be delivered from the reel 1 onto some one of the carriers 3, and be moved forward thereon to and over the table T or T'. And the grippers are so timed and operate that when the sheets come in position over the tables the grippers will close upon the tails of the sheets, see Fig. 4, then preferably, move forward slightly in the direction of 120 125 130

travel of the carriers and drop below the plane of the upper run of the carrier, see Figs. 1 and 3, and hold the sheets while the carrier moves from beneath the sheets 5 and the following carrier passes above the held sheet; and when the carrier passes from beneath the stopped sheet the grippers open and the sheet is dropped upon the receiving tables, as above fully explained.

10 What I claim is:

1. A sheet delivery apparatus comprising a plurality of receiving tables; a series of sheet carriers moving in an endless path around said tables, and adapted to pass 15 successively over the tables; means for directing sheets onto the carriers; and grippers adapted to engage the tail ends of the sheets on the carriers when they have been brought over the receiving tables, and to 20 hold the sheets until the carriers have passed from beneath the sheets, and then to release the sheets and permit them to drop upon the tables.

2. A sheet delivery apparatus comprising a plurality of receiving tables; a series of sheet carriers moving in an endless path around the tables and adapted to pass successively over the tables; means for directing sheets onto the carriers; and grippers 25 adjacent each table adapted to engage the tail ends of the sheets when they have been brought over the receiving tables by the carriers, and to hold the sheets until the carriers have passed from beneath the sheets, 30 and then to release the sheets and permit them to drop upon the table; and means for causing the grippers to drop beneath the plane of the carriers after they seize a sheet to permit the following carrier to pass over 35 the stopped sheet, substantially as described.

3. In a sheet delivery apparatus, the combination of a receiving table; a carrier moving in an endless path around the table 45 and adapted to carry a sheet above the table; tail grippers adapted to seize the tail of the sheet on the carrier when it is brought over the table; a rock shaft supporting said grippers; and means for rocking 50 said shaft so as to cause the grippers to rise and seize the tail of the sheet, and to release the sheet when the carrier has moved from beneath same, and then to retract out of the way of an incoming sheet.

55 4. In a sheet delivery apparatus, the combination of a receiving table; a carrier moving in an endless path around the table and adapted to carry a sheet above the table; tail grippers adapted to seize the tail of the 60 sheet on the carrier when it is brought over the table; a rock shaft supporting said grippers; and means for rocking said shaft so as to cause the grippers to rise and seize the tail of the sheet, then to depress the tail of 65 the sheet out of the path of the carrier, to

release the sheet when the carrier has moved from beneath same, and then to retract out of the way of an incoming sheet.

5. In a sheet delivery, the combination of a set of traveling carriers each comprising 70 a flexible platform adapted to receive and support sheets laid thereon and carry them to the point of deposit; means for seizing the tail end of a sheet lying on a carrier and arresting it at the point of deposit; and 75 means for causing the seizing means to depress the tail end of the arrested sheet so that a following carrier may move thereover while the sheet is arrested.

6. In a sheet delivery mechanism, the 80 combination of a series of sheet carriers each comprising a flexible platform or grid adapted to receive and support sheets laid thereon and carry same to the point of deposit, means for forwarding sheets onto such 85 carriers, and means for moving such carriers in an endless path; with grippers adapted to engage the tail end of a sheet when a carrier has brought it to the point of deposit, hold the sheet while the carrier 90 moves from beneath it, and then release the sheet and permit it to drop.

7. In a sheet delivery, the combination of a series of carriers each comprising a flexible platform adapted to receive and support sheets laid thereon and carry them to the point of deposit, means for feeding sheets onto such carriers, and means for moving the carriers in an endless path; with means for seizing the tail ends of the 95 sheets and arresting them at the point of deposit; and means for causing the seizing means to lower the tail end of the sheet so that a following carrier may pass thereover 100 while the sheet is arrested.

8. In a sheet delivery, the combination of a plurality of receiving tables; a series of sheet carriers each comprising a set of tapes adapted to carry sheets laid thereon to and over the said table, and means for moving 110 said carriers in an endless path; with means for feeding sheets onto the carriers in the direction of its travel; and devices adjacent each table adapted to seize the tail of a sheet when it is brought into position over such table, and hold the sheet until the carrier has moved from beneath it, and then to release the sheet and allow it to drop upon the table.

9. In a sheet delivery mechanism, the combination of a delivery table, a series of sheet carriers each comprising a flexible platform adapted to receive and support sheets laid thereon and carry same to the point of deposit, means for forwarding sheets onto such carriers at the upper run of their travel, and means for moving such carriers in an 115 endless path around said delivery table; with grippers adapted to engage the tail end of a sheet when a carrier has brought it to a 120

- point above the delivery table, hold the sheet while the carrier moves from beneath it, and then release the sheet and permit it to drop onto the table.
- 5 10. In a sheet delivery, the combination of a delivery table, a series of carriers each comprising a flexible platform adapted to receive and support sheets laid thereon and carry them to the delivery table, means for
- 10 feeding sheets onto such carriers on the upper run thereof, and means for moving the carriers in an endless path around the delivery table; with means for seizing the tail ends of the sheets and arresting them
- 15 above the delivery table; and means for causing the seizing means to lower the tail end of the sheet so that a following carrier may pass thereover while the sheet is arrested.
- 20 11. In a sheet delivery, the combination of a plurality of receiving tables; a series of sheet carriers each comprising a flexible platform adapted to carry sheets laid thereon to and over the said table, and means for
- 25 moving said carriers in an endless path; with means for feeding sheets onto the carriers in the direction of their travel while on the upper part of their run; and devices adjacent each table adapted to seize the tail
- 30 of a sheet when it is brought into position over such table, and hold the sheet until the carrier has moved from beneath it, and then to release the sheet and allow it to drop upon the table, substantially as described.
- 35 12. In a sheet delivery, the combination of a flexible carrier platform adapted to receive and support a sheet laid thereupon and carry it to the point of deposit, and means for moving said platform bodily to and from
- 40 the sheet receiving point; with means for seizing the tail end of the sheet lying on the platform and arresting and holding the sheet at the point of deposit while the platform moves from beneath the sheet, and
- 45 then releasing the sheet, substantially as described.
13. In a sheet delivery, the combination of a series of flexible carrier platforms adapted to receive and support sheets laid
- 50 thereupon and carry them to the point of deposit, and means for moving said platforms to and from the sheet receiving point; with means for seizing the tail ends of the
- 55 sheets lying on the platforms and arresting and holding the sheets at the point of deposit while the platforms move from beneath the sheets, and then releasing the sheets, substantially as described.
- 60 14. In a sheet delivery, the combination of a sheet feeding means, a traveling flexible platform adapted to have sheets laid there-

upon by such feeding means and to carry such sheets bodily to the point of deposit; means for seizing the tail end of the sheet lying on such platform and arresting it at

65 the point of deposit while the platform moves from beneath the sheet; and means for causing the seizing means to release the sheet when the platform has moved from beneath the sheet.

70 15. In a sheet delivery, the combination of a platform moving in an endless path and adapted to receive and support a sheet laid thereupon and carry it to the point of deposit, and means for moving said platform

75 bodily to and from the sheet receiving point; with means for delivering sheets upon the platform in the direction of its movement and means for arresting and holding the sheet lying on the platform by its tail end

80 at the point of deposit while the platform moves from beneath the sheet, and then releasing the sheet, substantially as described.

16. In a sheet delivery, the combination of a series of platforms moving in an end-
85 less path and adapted to receive and support sheets laid thereupon and carry them to the point of deposit, and means for moving said platforms to and from the sheet receiving point; with means for delivering 90 sheets onto said platforms in the direction of their movement as they move onto the upper run of their path; and means for seizing the tail ends of the sheets lying on the platforms and arresting and holding the 95 sheets at the point of deposit while the platforms move from beneath the sheets, and then releasing the sheets, substantially as described.

17. In a sheet delivery, the combination of a set of traveling platforms moving in an endless path and each adapted to receive and support a sheet laid thereon and carry same to the point of deposit; means for delivering sheets onto said platforms in 100 the direction of their movement as they move onto the upper run of their path; and means for seizing the tail end of a sheet lying on a platform and arresting it at the point of deposit, and means for causing the 105 seizing means to depress the tail end of the arrested sheet so that a following platform may move thereover while the sheet is arrested.

110 In testimony that I claim the foregoing as my own, I affix my signature in presence of two witnesses.
